UNITED STATES PATENT OFFICE.

WILLIAM B. MOSES, OF BROOKLINE, MASSACHUSETTS, ASSIGNOR TO GRAY & DAVIS INC., OF CAMBRIDGE, MASSACHUSETTS.

REGULATOR FOR DYNAMO-ELECTRIC MACHINES.

1,363,806.

Specification of Letters Patent. Patented Dec. 28, 1920.

Application filed October 18, 1915. Serial No. 56,475.

To all whom it may concern:

Be it known that I, WILLIAM B. MOSES, citizen of the United States, and resident of Brookline, in the county of Norfolk and 5 State of Massachusetts, have invented certain new and useful Improvements in Regulators for Dynamo-Electric Machines, of which the following is a specification.

This invention relates to apparatus for 10 controlling electrical energy and with regard to certain more specific features thereof to automatically operative cutout and regulating devices.

It is one of the objects of the present invention to provide a device of the above-said character which shall be compact and simple in construction yet efficient and reliable in its operation.

Another object of the invention resides in 20 the provision of simple and durable means suitable for use upon automobiles or the like, whereby vibratory movements of the armatures due to vibration of the engine or road irregularities are absorbed before directly 25 affecting certain contact points.

It is a further object of the invention to create a plurality of distinct magnetic fields thereby providing a plurality of means for controlling the movement of independently 30 arranged armatures. This permits location of the respective armatures if desired at points remotely apart, with each unaffected by movement of the other.

Other objects will be in part obvious and in 35 part specifically pointed out hereinafter.

The invention accordingly consists in various features of construction, combinations of elements and arrangements of parts which will be exemplified by the construction 40 hereinafter set forth and the scope of the application of which will be indicated in the following claims.

In the accompanying drawings, wherein is shown one of the various possible embodiments of the invention:

Figure 1 is a plan view of a cutout and regulator device embodying certain features of the invention. The cover is removed to more clearly disclose the interior construction.

Fig. 2 is a diagrammatic view of the de-

vice shown in Fig. 1 showing further the generator, battery, lamps and electrical circuits comprised by the system.

Referring now more particularly to the drawings, wherein similar reference characters refer to similar parts throughout the different views, there is indicated at 1 a base or support provided with side walls 2 and 3 and adapted to receive a cover (not shown). 55 Mounted upon the base 1 and insulated therefrom is a T-shaped auxiliary support 4 of iron or other suitable magnetic material. The stem 5 of the T member is perforated to receive and support a core 6 which latter has 60 mounted upon it the wire wound spools 7 and 8 respectively on opposite sides of the stem 5. The cross-bar of the T member has its opposite ends turned inwardly, and riveted to these ends respectively are flexible 65 strips of conducting material 9 and 10. These strips in turn carry armatures of rigid material designated as 11 and 12. The armature 11 extends transversely opposite one end of the core 6 and the armature 12 has a 70 similar location relatively to the other end of the core. A flexible arm 13 is rigidly and electrically connected to the strip or hinge 9 and carries the movable contact 14 which has a co-operative association with a fixed 75 contact 15, the latter being supported and insulated from the cross-bar of the auxiliary support. A yoke 16 is also secured to the hinge 9 and is formed with fingers 17 and 18 which alternately bear on opposite sides 80 of the contact carrier 13 in a manner and for purposes which will be hereinafter set forth. The yoke 16 has a third finger 19 which contacts with the fixed angle piece 20 to provide a stop for limiting the outward movement 85 of the armature 11.

The armature hinge 10 has likewise rigidly supported thereon a flexible arm 21 carrying the movable contact 22 which has a co-operative association with the fixed contact 23. The latter is supported by and insulated from the cross-bar of the auxiliary support 4. A rigid arm 24 is mounted on the hinge 10 and is formed with a finger 25 normally arranged a short distance out of 90 contact with the flexible spring arm 21. The latter is flexed normally to cause the

contact 22 to bear with substantial pressure upon the fixed contact 23 and cause a wiping action of the former upon the latter when making and breaking the contacts.

5 The finger 25 is designed to come into contact with the arm 21 provided the contacts unduly adhere thereby insuring separation of the contacts as intended.

The contacts 14 and 15 are normally apart, 10 the flexible arm 13 being held away by the finger 17 of the yoke 16 thereby preventing accidental closing of the contacts due to unintentional movement of the arm 13 as by shock or jar of the instrument. Upon movement of the armature 11 throughout the 15 early part of its range the contact 14 is moved against the contact 15. Further movement of the armature flexes the spring arm 13 and causes substantial pressure upon 20 the contacts. Still further movement of the armature brings the finger 18 to bear firmly on the arm 13 thereby limiting further movement of the armature. The movement of the armature through the final angle of 25 its range carries the finger 17 slightly away from the arm 13 and therefore the armature may move back and forth through a small angle without disturbing the contact relationship of the points 14 and 15.

30 From the foregoing it will be apparent that both sets of contacts have a wiping action and that the cutout switch is safeguarded against the making or breaking of the points due to vibrations caused by the 35 conditions of the service.

A regulator magnet is provided by winding the spool 8 with many turns of fine wire 26 and a cutout switch magnet is provided by winding the spool 7 with a large number 40 of turns of fine winding 27 and a smaller number of turns of coarse winding 28 the functions of which will be hereinafter explained.

45 For the purpose of varying the gap between each armature and its magnet a headed screw 29 of magnetic material is threaded into the core 6 at each end. A check nut 30 serves to bind a turn of spring wire 31 firmly in position and this wire has 50 an extended loop 32 adapted to engage with the knurls 33 of the head 34 of the screw. As the screw is rotated the longitudinal position of the head is varied and the same is held in 55 adjusted position by the engagement of the spring wire loop 32 with the head.

Upon the side walls of the casing there are provided three insulated terminals 35, 36, 37, and a grounded terminal 38. The wiring to and from these terminals will be 60 apparent upon a consideration of Fig. 2.

Referring to the diagram shown in Fig. 2 a generator is indicated at 39 having a shunt field 40, a storage battery at 41 and a lamp circuit at 42. At 43 is shown a resistance 65 connected between the terminals 36 and 37

adapted to be cut in and out of the field circuit as the regulator contact points open and close.

It is to be understood that this invention finds a special application to the lighting 70 system of an automobile and while obviously it may be adapted to various other devices its operation will be described with respect to its use with gasoline motor cars and engine driven generators.

75 Assuming the car at rest with the engine stopped the lamps are supplied with current from the storage battery. The positive side of battery and one side of the lamp circuit being grounded the circuit is completed 80 through the lamps and a conductor 44 subject, of course, to the usual switch control. Upon starting the engine to which is connected the generator armature, current is supplied to the field winding 40 through a 85 field circuit as follows: from the positive brush, as indicated, through the field winding 40, wire 45, terminal 36, wire 46, contacts 23 and 22, spring strip 21, hinge 10, the cross-bar of the auxiliary support as far as 90 the stem 5, through the stem 5 to the core 6, through the series or coarse winding 28 which is electrically connected with the core, through wire 47 to the terminal 37 and thence through the wire 48 to the negative 95 brush. The positive brush of the generator is grounded as indicated at 49 and a circuit is also established through the grounded terminal 38, conductor 50, potential coil 27, return wires 47 and 48, to the negative brush. 100

As the generator output increases due to building up with increase in speed of the engine the potential coil 27 is strengthened until the armature 11 is attracted and the spring arm 13 moved to close the contact 105 points of the automatic switch. Further attraction of the armature flexes the arm, exerting substantial pressure on the points and acts upon the armature to cause it to move the yoke finger 18 against the arm thereby 110 insuring good contact at the points. It is to be noted that there may be a drop in potential from this point without opening the contacts, as hereinbefore explained. A small 115 current in the series coil 28 which flows normally in the field circuit assists the potential coil 27 in its action. With the automatic switch closed, the battery and lamps are included in the generator circuit, the lamp circuit being as follows: from positive generator brush to ground to lamps 42, conductor 51, terminal 35, wire 52, contact points 15 and 14, arm 13, hinge 9, the cross-bar of the auxiliary support as far as the stem 5, through stem 5 to the core 6, thence through series winding 28, wire 47, terminal 37, wire 48, to the negative generator brush. The battery voltage having been overcome the generator now supplies the lamps through a 120 circuit in parallel with the battery. 130

From the grounded terminal 38 a conductor 53 extends to one end of the potential coil 26. The other end of this coil connects with the terminal 37 through a conductor 54, and the common negative armature wire 48 completes this circuit through the armature to ground. As the generator output increases to a predetermined point considered safe or desirable for the battery circuit the 5 potential winding 26 is energized to attract the armature 12 sufficiently to open the contact points 22 and 23 and direct the field current through the resistance 43. The field strength is thereby decreased reducing the 10 output of the generator for a given speed, which reduction reflecting on the regulator potential coil reduces the strength of the magnet and permits the contacts 22 and 23 to close restoring the original circuit. The 15 contact 22 is therefore vibratory in its action the periodicity of the vibrations being longer or shorter accordingly as the generator is driven at very high or only moderately high speeds.

20 It is undesirable to permit the generator voltage to continue below that of the battery while the latter is included in the circuit and this invention provides improved means centering about the automatic switch for cutting the battery out when its tendency is to discharge and motorize the generator. A slight excess of battery voltage over the 25 generator voltage causes a small reverse current to flow through the series coil 28 which bucks the action of the potential coil 27 tending to deenergize the switch magnet and permitting the spring hinge 9 to open the contact points. The battery and lamps are by this means cut out of the generator 30 circuit. It is to be noted that if for example, a 6 volt battery is employed and the apparatus designed to close the automatic switch at a generator voltage of 8 volts, the switch will not open until the generator 35 voltage drops below the battery voltage, that is, below 6 volts.

As the battery voltage opposes that of the generator it will be obvious that a taper charge of the battery is automatically effected. The resistance of the battery being 40 less when partially exhausted than when fully charged, it will receive more current under the former condition than the latter.

It is understood that taper charge devices have been known and used and that devices have been provided for safeguarding the battery by automatically weakening the generator field or fields, and that automatic switches have been known and used for cutting the battery into and out of the circuit. This invention, however, comprehends the provision of an extremely compact device and particularly one in which two distinct magnetic fields are created to coöperate with 45 separate armatures.

The stem 5 operates to magnetically bifurcate the instrument and eliminates the possibility of current regulation while at the same time a single core and comparatively small amount of winding are employed materially reducing the cost of manufacture. 70

As many changes could be made in the above construction and many apparently widely different embodiments of this invention could be made without departing from 75 the scope thereof, it is intended that all matter contained in the above description or shown in the accompanying drawings shall be interpreted as illustrative and not in a limiting sense. 80

Having described my invention, what I claim as new and desire to secure by Letters Patent is:

1. In a device of the character described, in combination, a support having two armatures flexibly mounted thereon, an electromagnet coöperatively associated with said armatures, fixed regulator and cut-out contacts, movable regulator and cut-out contacts carried by flexible arms extending 85 from said armatures respectively, and a controller arm for the flexible arm of the cut-out contacts comprising means for holding the cut-out contacts in firm engagement and means for providing a substantially positive 90 release, said last means being adapted to permit a range of movement of the corresponding armature before acting to release. 95

2. In a device of the character described in combination, a casing having terminals, a 100 T-shaped support arranged within said casing, a core fastened through the stem of the T-support, armatures spring supported respectively from each end of the cross-bar of the T-support, a compound winding about 105 the core on one side of said stem, a potential winding about the core on the opposite side of said stem, circuit controlling contacts operated by said armatures, and electric conductors for connecting the contacts 110 and windings with said terminals.

3. In a device of the character described in combination, a casing having terminals, a T-shaped support arranged within said casing, a core fastened through the stem of the 115 T support, armatures spring supported respectively from each end of the cross-bar of the T support, a compound winding about the core on one side of said stem, a potential winding about the core on the opposite side 120 of said stem, circuit controlling contacts operated by said armatures, adjustable means for varying the magnetic value of the gaps between said core and said armatures, and electric conductors for connecting the contacts 125 and windings with said terminals.

4. In a device of the character described in combination, a casing having terminals, a T-shaped support arranged within said casing, a core fastened through the stem of the 130

T support, armatures spring supported respectively from each end of the cross-bar of the T support, a compound winding about the core on one side of said stem, a potential 5 winding about the core on the opposite side of said stem, circuit controlling contacts operated by said armatures, adjustable means for varying the magnetic value of the gap between said core and said armatures, means

for retaining said last means in adjusted position, and electric conductors for connecting the contacts and windings with said terminals. 10

Signed at Cambridge, in the county of Middlesex and State of Massachusetts, this 15 ninth day of October, A. D. 1915.

WILLIAM B. MOSES.
